RECLAIMING APPARATUS

Theodore A. La Brecque, Elmira, N. Y., assignor
to The Hilliard Corporation, Elmira, N. Y., a
corporation of New York

Application November 14, 1936, Serial No. 110,847

1. Claim. (Cl. 196—16)

This invention relates to a structurally and functionally improved reclaiming apparatus and aims to provide an apparatus of an improved nature over that disclosed in my prior application 5 Serial No. 734,500, filed July 10, 1934, for "Refining apparatus and method".

Viewed from a more specific aspect, it is an object of the invention to provide an apparatus of this nature which is capable of being used 10 in connection with numerous types of liquids, but which is primarily intended for employment in connection with the reclaiming of oil.

As such, it is an object of the invention to furnish a unit of this type and which may be advantageously and readily utilized by ordinary 15 garages and service stations as well as central stations receiving spent oil or similar fluids from a number of individual garage or service men. Moreover, the apparatus may readily be operated 20 by unskilled employees to furnish entirely desirable and satisfactory results.

An additional object is that of designing a reclaiming apparatus which may be more or less permanently coupled to a power unit such as a Diesel engine plant, and which will operate in 25 such manner as to constantly reclaim and, if desired, redeliver the oil to the unit.

A further object of the invention is that of providing a reclaiming apparatus which will be 30 of extremely compact construction and in which, if it is desired to increase the capacity, this may be accomplished without expensive rebuilding operations.

A still further object is that of constructing 35 a unit of this type and in which such parts as require periodic inspection and renewal may readily receive proper treatment; such treatment involving minimum expense and requiring but a small amount of time on the part of an operator. Aside from such renewal treatments, 40 an apparatus constructed in accordance with the teachings of the present invention will require no attention whatsoever, despite the fact that it will function continuously or periodically as desired by the user.

An additional object is that of furnishing a 45 unit of the character described which will embody relatively few parts each individually simple and rugged in construction, and operating over long periods of time with freedom from all difficulties.

With these and other objects in mind, reference is had to the attached sheets of drawings 50 illustrating one practical embodiment of the invention, and in which:

Fig. 1 is a sectional side view of the apparatus;

Fig. 2 is a sectional side view of a pump unit which preferably forms a part of such assembly, this view being taken along the lines 2—2 and 5 in the direction of the arrows of Fig. 3;

Fig. 3 is a transverse sectional view taken along the lines 3—3 and in the direction of the arrows of Fig. 2; and

Fig. 4 is a sectional side view of a valve which 10 may be employed particularly where a number of reclaiming units form a part of one assembly.

In these views the numeral 5 indicates a tank which receives the fluid to be reclaimed. This tank preferably has adjacent its base a drain 6 15 and disposed within the tank is a cylinder 7 which has open ends through the upper of which the fluid to be reclaimed is poured. With a view to preventing the entrance of solids into this tank a screen 8 may be mounted in the cylinder 20 and at this time it will be observed that the lower edge of the cylinder terminates well above the base of the tank. An outlet 9 extends through the wall of the tank at a point well above the base of the latter and this outlet is connected 25 within the tank to a flexible tube 10 supported by a float 11 to have its intake end 12 normally lie well below the surface of the fluid disposed within the tank.

It is obvious that by this arrangement an operator 30 may simply casually discharge dirty oil or similar fluids into the cylinder 7 and large particles of foreign matter will remain in contact with the screen 8 which may be periodically cleaned. Water and other liquids having a 35 relatively high specific gravity will settle towards the bottom of the tank and these, together with such impurities as pass through the screen 8, may be periodically withdrawn through the drain 6. The intake end of pipe 10, due to the 40 manner in which it is supported, will always be in such position that there will be no danger of air entering through this conduit while at the same time this tube will be located so that it will be receiving fluid from the best possible strata 45 or zone within the tank. This will, of course, be true for the reason that any small particles of foreign material will not reach the zone in which the intake end 12 of the tube is located because to reach such a position they would have 50 to pass downwardly within cylinder 7, past the lower edge of the same, and then upwardly to the zone in which the tube end 12 is disposed.

The same will be true of foreign liquids which, if they have a tendency to stratify towards the 55

lower end of the tank, may readily do so while if they have a tendency to rise, they will remain within the upper end of the cylinder.

- The outlet 9 is connected to the main reclaiming apparatus as, for example, by a tube 13, which is preferably flexible so that the tank 5 may, if desired, be shifted within limits with respect to such apparatus. Such tube connects to a pipe 14 within which is interposed a cut-off valve 15. The pipe has its discharge end connected to a cylinder 16 mounted on the frame 17 of the unit and operating within this cylinder is a piston 18 connected to a rod 19. Adjacent the discharge end of the cylinder a check valve 20 is provided. A seating of this valve is assured by a spring 21, the tension of which is adjusted to an extent such that a deliberate and power actuation of the piston 18 is necessary to assure unseating of the valve.
- With a view to actuating the piston rod 19 a yoke 22 is provided and this yoke is connected to a pitman 23. The rod 19 is conveniently screw threaded and connection between the yoke or cross-piece 22 and the rod may be assured by the use of clamping nuts 24. It is thus obvious that by loosening these nuts and adjusting the same, the piston may have its zone of travel varied to increase or decrease the amount of fluid discharged by cylinder 16.
- Such discharge occurs into a pipe 25 with which a bulb 26 may be coupled so as to even out the flow of fluid and prevent the creation of a surge. Likewise, if desired, pipes 14 and 25 may be connected by a by-pass 27, the flow through which may be regulated by pressure relief valve 28. In this manner, if undue and improper pressures occur, no damage will result to the parts because the fluid will simply be recirculated. Pipe 25 is continued upwardly through the frame of the machine and may have a valve 29 interposed in its body. The construction of this valve and its purpose will be hereinafter more particularly described, but at this time it will be observed that pipe 25 is extended inwardly at a point beyond the valve and in the form of a coil or loop 30.
- Mounted adjacent the upper end of the frame 17 is a casing, including side walls 31, which is normally sealed by a cover 32. This cover may be hingedly mounted as at 33 and clamped in sealing position as, for example, by wing nuts 34 mounted upon screw threaded rods 35. Positioned below the casing is a base 36, the upper face of which is roughened. While such roughening may include a number of desired configurations, it is preferred that the same include a series of pyramidal projections. Adjacent its center the base is recessed to accommodate a screen plate 37, and at which point it is formed with an opening 38.
- The base or lower portion of casing 31 includes a perforated plate 39 and this plate is positioned upon base 36. Interposed between these surfaces is a layer of material 40 conveniently mounted and retained in position by a ring 41 underlying plate 39 and encircling side walls 42 upon which the base 36 is mounted. Preferably the fabric 40 is canvas, although other materials may be employed, and it will be obvious that this layer 40 will generally conform to the projections presented upon the upper face of base 36, although it will never be capable of completely conforming to the trough portions or channels presented between these projections. As a consequence the latter will never be completely obstructed and

fluid may flow through the same toward the screen plate 37 and opening 38. At this time it is also to be noted that interposed between the fabric layer 40 and plate 39 is a layer 43 of filtering material such as suitable paper, so that fluid, in passing through the openings of plate 39, will have to traverse the layer of filtering paper 43 as well as the fabric layer 40, before it may flow between the projections of base 36 to the opening 38.

Arranged above plate 39 is a mass of filtering material. While this mass of filtering material may include various types of filtering material, it has been found to be preferable to utilize fuller's earth. This is scattered upon plate 39 until it has reached a depth substantially equal to one-half the height of walls 31. At this point a layer 44 of filtering material such as blotting paper is preferably arranged within the casing, and the casing is filled to a greater depth with a mass of fuller's earth 45 and above this there is disposed a layer of cotton waste or similar material 46. This entire filtering body is compressed by a coarse screen 47 which may be weighted as at 48 and/or which may be provided with springs 49 contacted by the under-face of the cover, so as to firmly press the screen against the upper surface of such filtering body. Ordinarily, when thus compressed, such body may rise within the side walls to the position shown in the drawings, although it may include a mass of material which may fill this casing portion to one-half its depth. Thus, additional space is furnished for filtering material to be used where a large amount of oil or other liquid to be reclaimed is passing through the body or where it is desired to not frequently renew such body.

The coil 30 has its outlet end connected to a flexible tube 50 which may include heat insulating characteristics. The end of this tube discharges through an opening 51 preferably centrally disposed in the cover 32. As afore brought out, walls 42 extend below the base 36 and these define a space within which a unit 52 is disposed. This unit, as taught in my prior application afore referred to, may embrace a generally conical body having upon its upper face a series of arcuate baffles. The end of each of these baffles is spaced from a transversely extending wall 53 to an extent such that an aggregate tortuous passage is presented extending from the center of body 52 to the edge thereof, at which point liquid may discharge through an opening 54. The opening 54 is coupled by a pipe 55 to a cylinder 56 within which a piston similar to piston 18 acts and within which there is also preferably disposed a check valve assembly similar to that heretofore described at 20 and 21. This piston is actuated by a rod 57 connected to the cross-piece or yoke member 22, and fluid is discharged from this cylinder through a tube 58 which is connected to a receiving tank (not shown).

In this manner it will be obvious that pitman 23 serves not alone to pump fluid to the filtering unit, but also serves to distribute the reclaimed fluid. This pitman is driven by a motor 59, the shaft of which may conveniently mount a fan 60 and serves to drive a worm and worm wheel (not shown) disposed within casing 61. The worm wheel rotates a plate 62 to which the upper end of pitman 23 is coupled, and it will be observed that any proper adjustment may be included, so that if desired the stroke of the pit-

man may be varied. The drive shaft is continued beyond the casing 61 and couples with a vacuum pump generally indicated as at 65. This pump has its intake end coupled as at 66 to a distillate receiving tank 67. Such tank is connected by a coil 68 with the interior of the casing within which unit 52 is disposed, and it will be appreciated that the fan 60 not alone serves to cool the motor, but also acts to circulate air past the coil 68, thus emphasizing the condenser feature of the latter.

Now, with a view to providing means which will serve to separate distillates from the fluid passing through opening 38, it will be observed that a suitable heater 69 is employed preferably at a point below unit 52. The degree of heat may be regulated by a control 70 and within which in well known manner, a thermostat may be provided to constantly maintain the temperature for which the unit has been set. It will also be observed that the coil 30 is disposed closely adjacent the heater 69 and according to an ideal setting of these parts, it has been found desirable to maintain the heater active to a point where the coil has a temperature of approximately 300° F., while the unit 52 and the chamber within which the same is disposed is maintained at a temperature of from 350° F. to 400° F. It is thus perfectly obvious that water and undesired distillates will be vaporized within the chamber occupied by unit 52 and drawn off through coil 68. The outlet end of vacuum pump 66 discharges into a casing 71 in turn having an outlet pipe 72 which is preferably extended to the outside atmosphere and it will be noted that this pipe has connected to it a relatively minute discharge tube 73 so as to provide for a constant discharge of moisture from this exhaust line.

In operation it is to be understood that the operator will fill casing 31 with filtering material, as afore specified. If oil is being reclaimed, he will dump oil into tank 5. He will now throw the switch 74 which is connected in a conventional manner to actuate motor 59 and heater 69. Of course, prior to these operations the zone and range of travel of the piston 18 will have been adjusted to conform to the requirements of the particular apparatus under consideration. Thereupon, oil that is reclaimed will flow through tube 13, cylinder 16 and tube 25. Also, as afore brought out, if some obstruction exists, the bypass 27 will function to prevent damage to the parts. A surge flow will be prevented, as for example, by bulb 26, and fluid will flow upwardly through tube 25 and coil 30 where the emulsions will be broken up. In its flow from the coil the liquid will not be materially cooled by the time it passes through opening 51 because of the heat insulating characteristics preferably embodied in tube 50. The oil will pass through the layers of filtering material defined by the walls 31 and thence through the openings in plate 39. Thereupon it will flow through the layer of filtering material 43 as well as the fabric 40, and screen plate 37, to pass through opening 38. The oil will flow through the tortuous passages of the vaporizer unit 52 and will be heated during such flow. As a consequence the distillates will be sucked out of this chamber and through condensing coil 68 while the oil, relieved of such distillates, will flow through opening 54 and tube 55, through pump cylinder 56 and to a convenient receptacle. Such distillates as are not deposited within tank 67 will flow through the same and through the passage 66 and pump

65 to casing 71 and tube 72 and be suitably discharged, it being observed again as afore brought out that due to the relatively small discharge tube 73, moisture will be exhausted from this line.

It is, of course, to be understood that in addition to providing by-pass 27, a circuit breaker (not shown) may be included in the line to switch 74. Accordingly an additional safeguard will be furnished in the event of the electrical load becoming too great. As will also be noted, clean-out plugs 75 may be provided at convenient points in the apparatus so that a clogging of the same will be virtually precluded and a vacuum gauge 76 may be coupled to the vaporizing chamber so that an operator will be entirely cognizant of the degree of vacuum existing within the same. Moreover, a petcock 77 may be coupled to the cover or any other suitable casing portion to allow air to flow into the same when this is desired, but normally it will be understood that this valve is closed and that the entire casing, including the vaporizing chamber, provides a substantially airtight enclosure.

When it is desired to close down the machine, this is done by simply turning off valve 15 and opening petcock 77. Under these circumstances, air is drawn into the interior of the casing and through the body of the filtering material. This will dry such material and after adequate time has elapsed the switch 74 is thrown so that both the heater and the motor are disconnected. The cover 32 is now released and swung upwardly and the operator lifts the side-walls 31 together with plate 39 from the base 36. The filtering material—incident to the passage of the oil therethrough—is not readily pliable and possesses the characteristics of a plastic. Therefore, unless this casing section receives a severe jar, the material will not pass through the openings of the plate 39 and this material may simply be discarded. While the mass of filtering material should be renewed at relatively frequent intervals (for example, once every twenty-four hours) the layer of fabric 40 will have to be renewed only infrequently. Of course, it should be periodically cleaned and the layer of filtering paper 43 should be renewed whenever necessary. Obviously, upon the material being again built up within the casing body, the operation of the unit may be continued by simply again opening valve 15 and closing valve 77 and switch 74.

While the vacuum pump 65 may include a number of different constructions, it is preferred, as illustrated in Figs. 2 and 3, that it embrace an annular chamber 78 within which an eccentrically disposed rotor 79 is mounted. Passages 80 and 81 afford access to the rotor chamber and a number of spring pressed vanes 82 are mounted by the rotor and serve to impel fluid through the chamber. In advance of the vanes or blades the rotor is reduced as indicated at 83. The reason that this construction is preferably resorted to is because when the pump is not operating fluid naturally collects at the bottom of the rotor chamber and some of this fluid will be disposed in advance of the vanes. When the pump is started this fluid which may be rather heavy and chilled, moves in advance of the vane and due to the speed of the rotor may not be discharged through outlet opening 81. Thus, under these circumstances, the spaces provided at 83 accommodate this fluid which is not compressed to an extent such that a decided load would be created which might stall or injure 75

the mechanism and this fluid will be eventually discharged through port 81.

It has, moreover, been found, in connection with this pump, that a lubricating system including conduits 84 should be employed. Lubricant is forced through these conduits so that the uncondensed vapor passing through the pump will not corrode the pump parts because the latter are being constantly irrigated with lubricating oil which is preferably changed at the end of twenty-four hours' operation.

Finally, it may be desired to couple a number of units embracing filtering bodies and vaporizers to, for example, a single operating mechanism embracing the pressure pumps and vacuum pump. In such case, valves 29 are connected to each filtering and vaporizing unit so as to assure an even distribution of fluid thereto. These valves, as illustrated in Fig. 4, may each include a body 29 formed with an intake port 85 and an outlet port 86. A tubular valve body 87 may slidably cooperate with the intake port to control the flow of fluid therethrough and a spring 88 may normally urge this body to such a position. A screw threaded stem 89 is mounted by the casing and is provided with a pin 90 having slotted connection with the tubular body 87. Accordingly the tension on the spring may be adjusted although the body is at all times free to move to unseated position. The lower end of body 87 is slotted preferably as at 91, and it follows that incident to a given pressure a certain amount of fluid may pass through casing 29. Thus, these valves associated with each other will serve to equalize the flow to the same, it being of course obvious that in such an event the piston rod 19 is adjusted to supply a greater volume of fluid to the several pipes extending to the units and also, if desired, the pitman may be connected to opening 64 so as to provide greater travel for the pistons.

In such an installation a single receiving tank 5 may be employed as may also a single distillate receiving tank 67. In the latter event a suitable connection (not shown) will be furnished, leading from the vaporizing chambers of the several units to the tank. In conclusion, it will be observed that the distillate may be drawn off through a valve 92 or any other convenient

passage, and it will be appreciated that regardless of the number of units provided, the check valve associated with cylinder 16 is under sufficient spring tension that under no circumstances will the vacuum, which might act through the supply pipe, be capable of unseating the check valve.

Finally, it will be understood that, if the apparatus be directly coupled, for example, to a Diesel engine or other oil consuming unit, the latter may deliver oil to be reclaimed to the tank 5, or if desired the unit might be directly coupled to the tube 13. In such an installation while the oil which has been reclaimed might be discharged through tube 58 to a suitable receptacle, it will usually be more desirable to connect this tube directly to the oil consuming unit, thus avoiding all unnecessary apparatus.

From the foregoing it will be appreciated that, among others, the several objects of the invention as aforesaid are achieved. It will be obvious that numerous changes in construction and rearrangement of the parts might be resorted to without departing from the spirit of the invention as defined by the claim.

Having thus described the invention, what is claimed is:

A reclaiming apparatus including a casing to contain a body of filtering material and being formed with openings in its upper and lower faces, means providing a vaporizing chamber below said casing, said chamber being formed with an outlet opening through which unvaporized liquid may discharge, said chamber being formed with a further outlet opening for the passage of vaporized liquids, a tube connected to the opening formed in the upper face of the casing, said tube being extended to provide a preheating coil, a pump including a plurality of cylinders and pistons within the same, means for moving said pistons with respect to said cylinders, the end of said tube being connected to one of said cylinders whereby liquid under pressure is supplied to said casing, and a tube connected to the second of said cylinders and to the liquid outlet opening of said vaporizing chamber for positively withdrawing liquid through said opening.

THEODORE A. LA BRECQUE.
